UNITED STATES PATENT OFFICE

JOHN C. SCOVEL, JR., OF CHICAGO, ILLINOIS, ASSIGNOR TO THE CREAMERY PACKAGE MFG. COMPANY, OF CHICAGO, ILLINOIS, A CORPORATION OF ILLINOIS

REFRIGERATED AGITATING DEVICE

Application filed February 9, 1928. Serial No. 252,954.

The invention relates to refrigerated agitating devices, more particularly of the type illustrated in the co-pending application of George E. Wallis and John C. Scovel, Jr., Serial No. 137,417, which are adapted for cooling and stirring the contents of a liquid container or storage tank.

An agitator of this type is provided with a refrigerant chamber, and is operatively supported within the tank upon a shaft having a bearing in a wall of the tank and extending therethrough for actuation by means outside of the tank, the shaft being provided with passages for the admission and discharge of refrigerant to the agitator.

In the use of a refrigerant which is expanded within the chamber of the agitator, it is desirable to direct the refrigerant entering the chamber against a wall of the agitator outwardly contacting the liquid being agitated and cooled, and it has been found in practice that, where the entering refrigerant first strikes a spot on the wall of the agitator, an accumulation of frozen liquid on the outside of the agitator occurs opposite the spot of such contact.

Difficulty has been experienced also with the freezing of the shaft in its bearing in the tank wall by reason of the extremely low temperature occasioned in the portion of the shaft attached to the agitator wherein the refrigerant is expanded.

It is an object of the present invention to provide an agitator construction in which the incoming refrigerant is directed into the expansion chamber within the agitator in such manner that no accumulations of frozen liquid, within which the agitator is operating, is formed on the face of the agitator.

Another object is to provide a bearing construction for operatively supporting the shaft of an agitator of this type, which insulates the bearing surfaces against the low temperatures in the shaft caused by its heat conducting attachment to the agitator and by the gas passing within it, and prevents the freezing or binding of the bearing.

Other objects and advantages will be apparent in the following detailed description of a preferred embodiment of the invention

which is illustrated in the accompanying drawings. It will be understood, however, that various changes in form, construction and arrangement may be made by those skilled in the art without departing from the scope and spirit of the invention as expressed in the appended claims.

Referring to the drawings,

Figure 1 is a sectional view in elevation of the agitator and its shaft with the associated parts as mounted in the side wall of a storage tank, the latter being shown in fractional part.

Fig. 2 is a front elevation of the agitator illustrating the location of the agitating blades on the front face of the agitator and the relation thereto of the inlet openings for admitting the refrigerant to the expansion chamber within the agitator body.

In the drawings the numeral 1 indicates the lower portion of a double-walled storage tank supported on standards, of which one is indicated at 2. Positioned in the side walls of the tank is a conventional bearing block 3 having a conventional packing gland, indicated at 4, and within which bearing and gland is operatively supported a shaft extending into the tank and operatively carrying the agitator 5.

The agitator shaft comprises a tubular drive shaft 6 within which is positioned and spaced from the inner walls thereof an inner tube 7. As hereinafter described, the inner tube 7 forms an inlet passage for refrigerant fluid to a chamber in the agitator head, and the space between the inner tube 7 and the inner wall of the tubular shaft 6 provides a discharge passage for the return of the refrigerant from the agitator head.

The function of the shaft as a conduit for the refrigerant gas, together with the close proximity of the agitator with its expansion chamber to the tank wall bearing and the heat conducting attachment of the agitator upon the shaft, causes extremely low temperatures in that portion of the shaft. To prevent the freezing of lubricant or liquid seeping between the bearing surfaces of the shaft and its bearing block, I have provided an outer journal sleeve 8 mounted

concentrically upon the shaft 6 and extending for a substantial distance outward from the opposite ends of the bearing block 3 and packing gland 4 in which the sleeve 8 is operatively supported. The sleeve 8 is end-
 5 wardly rigidly supported upon the shaft, and intermediately provides a substantial annular space between the sleeve and the shaft, which is preferably filled with any suitable
 10 heat insulating material 9. By this novel construction, the temperature of the insulated journal sleeve 8 is always maintained above that which would cause the bearing lubricant, or any seepage between the bearing surfaces, to be congealed and interfere with the free
 15 operation of the shaft.

The agitator 5 comprises a hollow body portion constructed of the rear wall 10 and a preferably cone-shaped front wall 11, upon
 20 which latter are formed vanes 12 of any suitable contour for the agitating movement of the liquid within the tank by the rotation of the agitator.

A hub member 13 is axially positioned in
 25 the agitator body extending from front to rear and sealed to the walls 10 and 11 as by welding or other suitable method. The hub member 13 is rearwardly adapted to receive the tubular shaft 6 rigidly secured therein
 30 for the support of the agitator, and preferably, also, supports the adjacent inner end of the insulated journal sleeve 8 secured within a suitable shoulder formed on the hub.

The hub 13 is provided with an axial passage 14 communicating with and forming a continuation of the interior of the tubular shaft, the passage 14 having lateral ports 15 opening into the interior of the chamber 16 formed by the agitator walls 10 and 11. A smaller axial passage 17 is formed in the forward portion of the hub 13, also having lateral port openings 18 communicating with the chamber 16. The passage 17 forms a bearing
 40 for the end portion of the stationary inner tube 7 which communicates with the radial ports 18 and extends rearwardly through the tubular shaft 6 in spaced relation thereto.

The inner tube 7, forming, as previously described, the inlet conduit for the refrigerant under pressure, the latter is delivered to the expansion chamber 16 through the port openings 18, the latter being preferably
 55 formed to direct the expanding fluid against the front face of the agitator for more effective use of its heat absorbing quality during expansion. When the ports 18 are so positioned that the entering fluid strikes the front face of the agitator at any portion of the latter other than directly opposite to the vanes 12, an accumulation of frozen liquid forms outwardly of the spot of contact. By arranging the ports 18 so that the fluid is directed into contact with the front wall 11

immediately beneath the respective agitating blades or vanes 12, the heat conductivity of the mass of the blades 12 serve to prevent the formation of any frozen liquid immediately over the inlet ports, and the present structure provides one such inlet port beneath each of the blades or vanes.

The operating shaft 6 is supported outside of the tank in a bearing support 19 mounted as herein illustrated upon a bracket 70 20 secured to the outer wall of the tank. The shaft 6 also carries a driving pulley 21 which may be belted to any suitable source of power, not herein shown.

Mounted upon the rearwardly extended 80 end of the tubular shaft 6 is a stationary casing 22 having a bearing for the end of the shaft, the latter being operatively sealed in the bearing by a conventional packing gland indicated at 23. The casing 22 is constructed with an inner enclosed chamber 24 which is in communication with the open end of the tubular shaft 6. The stationary inner tube 7 extends through the end wall of the casing, passing through an opening therein and 90 being secured in a cap 25, the latter effecting a closure of the opening and being supported in sealed contact with the casing wall as by means of bolts 26.

The cap 25 carries a connection indicated 95 by the pipe 27 with a supply of refrigerant fluid transmitted to the inner tube 7 through the connecting passage in the cap. The casing 22 is provided with another opening communicating with the inner chamber and 100 adapted to receive a pipe connection 28 for the discharge of the refrigerant returned through the shaft 6, and the return of the refrigerant thereby to the source of supply. The casing 22 is stationarily supported by 105 means of a bracket 29 secured to the casing and the main bracket 20.

I claim as my invention:

1. In combination, a liquid container, an agitator positioned in said container and having an enclosed chamber, a shaft operatively supporting said agitator and having passages therein communicating with said chamber for the flow of refrigerant fluid to and from said chamber, said shaft extending through a 110 wall of said container, a journal sleeve mounted on said shaft in spaced relation thereto, and a bearing block mounted in a wall of said container and operatively supporting said journal sleeve.

2. A device of the class described, comprising an agitator having a hollow body enclosing an inner chamber, a tubular shaft for the operative support of said agitator having inward communication with said chamber, a 125 journal sleeve rigidly mounted on said shaft in spaced relation thereto, insulating material between said shaft and said journal sleeve, and a journal operatively supporting said bearing sleeve.

3. A device of the class described, comprising an agitator having an enclosed chamber, a hub member secured in said agitator having frontward and rearward passages communicating with said chamber, a tubular shaft operatively supporting said agitator and secured in said hub member in inner communication with said rearward passages, a tube within said shaft having a bearing support in said hub and communicating with said frontward passages, a journal sleeve mounted in concentric spaced relation to said shaft and having its forward end secured to said hub, and a bearing operatively supporting said bearing sleeve.

4. In combination with a liquid container, a hollow shaft journaled in a wall of said container, a hollow agitator within said container secured to said shaft for rotation therewith, an agitating vane disposed on the outer face of said hollow agitator, said shaft having inner communication with the interior of said hollow agitator, and a tube positioned in said hollow shaft extending into said agitator and having a port for communication with the interior of said agitator, said port opening adjacent the wall of said agitator carrying said vane and immediately opposite the position of said vane on said wall, said tube and hollow shaft forming inlet and outlet passages for a supply of refrigerant to and from said hollow agitator.

5. In a device of the class described, an agitator having front and rear walls marginally joined and centrally spaced to form a chamber therebetween, a hub supported in said front and rear walls and having a passage with a constricted front portion extending adjacent said front wall and having an enlarged rear portion opening into said chamber adjacent said rear wall, vanes mounted outward of the front wall of said agitator, ports in said hub communicating with said constricted portion of said passage and opening within said chamber immediately opposite the position of said vanes respectively upon said front wall, a hollow shaft secured to said hub for operative support of said agitator and having communication with the enlarged portion of said passage, and a stationary tube positioned within said shaft having a fluid tight bearing in the constricted front portion of said passage and communicating therewith.

55. In testimony whereof, I have hereunto affixed my signature.

JOHN C. SCOVEL, JR.
